(57) **CLAIM**

The ornamental design for a chew toy substantially as shown and described.

DESCRIPTION

FIG. 1 is a top, front, right 3D perspective view of a chew toy of FIG. 1 in accordance with our new design.

FIG. 2 is a top, rear, left, 3D perspective view thereof.

FIG. 3 is a front elevation view thereof.

FIG. 4 is a rear plan view thereof.

FIG. 5 is a top plan view thereof.

FIG. 6 is a bottom plan view thereof.

FIG. 7 is a left side view thereof.

FIG. 8 is a right side view thereof.

FIG. 9 is a top, front, right 3D perspective view of a first variant of the chew toy.

FIG. 10 is a top, rear, left, 3D perspective view thereof.

FIG. 11 is a front elevation view thereof.

FIG. 12 is a rear plan view thereof.

FIG. 13 is a top plan view thereof.

FIG. 14 is a bottom plan view thereof.

FIG. 15 is a left side view thereof; and,

FIG. 16 is a right side view thereof.

The broken lines illustrate portions of the chew toy that form no part of the claimed design.

1 Claim, 8 Drawing Sheets
